Application January 30, 1943, Serial No. 474,134

6 Claims. (Cl. 230—101)

This invention relates to vacuum pumps and particularly to diffusion or condensation pumps useful for increasing the pumping speeds of mechanical pumps at relatively high backing pressures.

The use of diffusion pumps, particularly in industrial applications, has been restricted by the fact that such pumps, as heretofore constructed, have not operated satisfactorily except under exceedingly low backing pressures, of the order of $\frac{1}{2}$ mm. of mercury, or less. The cost of producing and maintaining such low backing pressures is prohibitive for most industrial applications of vacuum pumping.

Accordingly, an object of this invention is to provide a vacuum pump of the type referred to embodying novel principles of pump construction by which it is enabled to operate efficiently to produce high pumping speeds at comparatively high backing pressures of from 1 to 3 mm. of mercury, or even higher. A further object is to provide such a pump which is comparatively inexpensive to construct and which is more economical of pumping fluid than prior pumps of its type.

These and other objects and advantages of the invention will be readily understood from the ensuing particular description, in conjunction with the appended drawings, wherein:

Fig. 1 is a vertical section view of a preferred embodiment of pumping apparatus of the invention;

Fig. 2 is a transverse section view on the lines 2—2 of Fig. 1;

Fig. 3 is a vertical section view of a portion of pumping apparatus, showing modified construction;

Fig. 4 is a transverse section view on the line 4—4 of Fig. 3;

Fig. 5 is a transverse section view on the line 5—5 of Fig. 3.

Diffusion pumps, as usually constructed, have a pumping chamber interconnected at opposite ends with the system undergoing exhaustion and with the backing pump. Vapors of a pumping fluid are discharged from a jet in the low pressure end of the chamber where they expand, flow toward the high pressure end of the chamber, and condense on its walls. According to generally accepted theory, these vapors perform their pumping function by entraining molecules of gas from the system being exhausted and carrying them along toward the high pressure end of the chamber. In some cases there are several vapor jets arranged in series along the pumping chamber.

In prior pumps of this character, the jets have

been of the so-called "umbrella" or "mushroom" type, in which the vapors flow in a substantially laterally continuous stream from one wall of the chamber, this stream usually being deflected away from the low pressure end of the chamber by an inclined shield which confines the stream between itself and this wall of the chamber. Such a jet exposes only one side of the vapor stream to the gases in the chamber, the side away from the chamber wall from which the stream is discharged, as there is no way in which the gases can get between the vapor stream and the wall.

We have discovered that an improved operation is obtained by the use of a novel jet of the invention by which the vapors are discharged into the chamber in spaced relation from the chamber walls, the jet comprising, at least in part, separate, laterally spaced vapor ducts providing open spaces between them through which the gases can circulate from one side to the other of the jet and thus contact opposite sides of a vapor stream produced by the jet. Preferably, the ducts are provided with individual, spaced nozzles which discharge separate streams of vapors between the walls of the chamber.

We have also found that the pumping action of such a jet is enhanced by providing in the pumping chamber one or more restricted passages for conducting the vapors from the jet toward the high pressure end of the chamber, such passage or passages preferably diminishing in width between their opposite ends, the jet being so arranged as to discharge the pumping vapors into the mouth or mouths of such passage or passages in spaced relation from the walls of such passage or passages so that the vapors issuing from the jet are allowed to expand as they enter the passage or passages and are exposed to the gases in the chamber.

40 The jet and co-operating restricted passages are preferably preceded in the low pressure end of the chamber by another pumping vapor jet which may be of the conventional umbrella type.

45 The invention also provides other improvements in the construction of diffusion pumps as will hereinafter appear.

In the form of apparatus shown in Figs. 1 to 3 of the accompanying drawings, a vertically arranged hollow cylinder 10 provides in its interior the main pumping chamber. The cylinder 10 is provided at its upper end with an annular projecting flange 12 by which it may be connected into the system to be exhausted (not shown). The lower end of the cylinder is closed by a bottom wall 14. Cylinder 10 is surrounded by a

jacket 16 spaced therefrom, this jacket being attached at its upper end to the flange 12 and at its lower end being closed by a bottom wall 18 spaced from the bottom wall 14 of the cylinder 10. The space between cylinder 10 and jacket 16 receives cooling water through connections hereinafter described.

A conduit 30 opens through the lower part of cylinder 10 into the high pressure end of the main pumping chamber, extending therefrom laterally and upwardly for a considerable distance and being provided at its upper end with an annular flange 32 by means of which it may be connected to the suction line of a suitable backing pump (not shown).

Located below the cylinder 10 is a boiler 40 in which there is maintained a supply of pumping fluid. A firebox 44 is provided beneath the boiler in which is placed a gas burner (not shown) or other suitable heating unit. Flues 46 extend upwardly from the firebox through the top of the boiler.

A chimney 48 extends upwardly from the boiler through the bottom wall 18 of jacket 16 and the bottom wall 14 of cylinder 10, substantially axially of the cylinder. The upper end of the chimney extends into the low pressure, upper end of the cylinder 10 and is closed by an end wall 50. An inverted conical shield 52 is attached to the wall 50 by a screw 54 and extends down around the upper end of the chimney which is provided, near its end wall 50 and above the lower edge of shield 52, with a ring of small apertures 56. The shield 52 co-operates with the upper end of the chimney and the apertures 56 to form a conventional umbrella type jet. The annular space between the chimney 48 and the cylinder 10 forms the main pumping chamber.

Within the pumping chamber there is mounted an annular partition 58 which is attached at its outer side to the inner wall of cylinder 10 and at its inner side to the chimney 48. Through the partition there extend a plurality of passages 60 forming sub-passages in the pumping chamber, there being eight such passages provided in the apparatus illustrated in Figs. 1 and 2 (see Fig. 2). Each of the passages 60, as shown, decreases in cross-section from its upper, inlet end, for a distance somewhat more than half its length, then increases in cross-section to its lower, outlet end, so that a stream of vapor or gas passing through the passage first contracts and then expands.

In the pumping chamber above the partition 58 there is provided a vapor jet comprising a plurality of individual vapor ducts 62, there being eight such ducts in the illustrated apparatus, arranged radially around the chimney and each co-operating with one of the passages 60. Each of the ducts 62 comprises, as shown, an elbow pipe 64 attached at one end to the chimney 48 and communicating with the interior thereof through a port 66. The opposite end of the elbow pipe 64 extends downwardly and has attached thereto a nozzle 68 extending therefrom to the upper end of one of the passages 60. Nozzles 68 have, as shown, an inwardly flaring, short inlet passage 70 and a relatively long, gradually outwardly flaring outlet passage 72. The lower end of the nozzles 68 is of smaller diameter than the adjacent upper end portion of the corresponding passage 60, providing space therebetween for vapors and gases to enter the passages 60 from the portion of the pumping chamber above the partition 58.

In operation, the boiler is provided with a quantity of suitable pumping fluid such as mercury or a heat stable organic compound having low vapor pressure at room temperature. Heat is applied causing vaporization of the fluid, the vapors rising into the chimney 48. Some of these vapors, reaching the top of the chimney, flow outwardly through the apertures 56 and are directed downwardly and outwardly by the shield 52, diffusing into and filling the main pumping chamber above the partition 58 entraining molecules of gas from the system undergoing exhaustion to which the pumping chamber is connected. Some of the vapors flow out through the ducts 62, contracting in the passage 70, expanding as they proceed along the passage 72 and expanding further as they leave the ducts and enter the mouth of one of the passages 60. These vapors then flow downwardly through the passages 60, contracting until they reach the narrowest portion of the passage and then expanding as they proceed to the bottom of the passage from which they expand into the portion of the main pumping chamber below the partition 58. The vapor streams from the ducts 62 act to draw the vapors and gases from the upper part of the pumping chamber therewith through the passages 60 and into the lower part of the pumping chamber. As the vapors proceed downwardly they condense on the walls of the pumping chamber and flow downwardly thereon, condensed liquid in the upper part of the chamber flowing downwardly on the walls of the chamber and the walls of the passages 60 into the lower part of the chamber. The gas molecules carried into the lower or high pressure end of the main pumping chamber are drawn off through the conduit 30 by the suction of the backing pump.

The spaces between the pipes 64 and separating the nozzles 68 from each other, from the chimney 48, which forms one wall of the pumping chamber, and from cylinder 10, which forms the other wall of the pumping chamber, provide passageways through which the gas and vapor mixture in the upper end of the chamber freely circulates so that the vapor streams issuing from the nozzles are exposed on all sides to the vapor gas mixture. A much more efficient pumping or entraining action results than is obtainable with a conventional umbrella type jet, such as shown at the upper end of the pumping chamber, in which the vapor stream issuing from the jet is exposed on one side only to gas molecules being exhausted, in the narrow space between the deflector shield of the jet and the outer wall of the chamber. Moreover, due to the provision of the constricted passages 60 and their relation to the ducts 62 of the jets, the vapors issuing from the ducts expand while they are exposed to the vapors and gases in the chamber above them, then contract and again expand as they flow downwardly through the passages, and this expansion, contraction, expansion of the vapor streams increases their pumping action.

To collect the condensed pumping liquid and return it to the boiler for re-use, there is provided, in the underside of conduit 30, near the cylinder 10, a pipe 74 extending downwardly to a T connection 76 with the boiler. Connection 76 is provided with a bottom cleanout plug 78, and with a side plug 80 which may be removed for the purpose of introducing new fluid into the boiler. The inner surface of the inner bottom wall 14 of the cylinder 10 is inclined downwardly toward the conduit 30 so that liquid is caused to

flow thereon by gravity into the bottom of conduit 30 and thence into the pipe 74.

To promote condensation of the pumping vapors the space between the jacket 16 and cylinder 10 is continuously supplied with cooling water through a pipe connection 82 opening through the bottom wall 18 of the jacket. Also, the lower part of the chimney 48 is surrounded by an outer wall or jacket 84 extending from the boiler to a point just above the partition 58. Between jacket 84 and the chimney there is provided a small space 86 which is preferably evacuated, and sealed at its opposite ends. We have found that this jacket and evacuated space between it and the chimney effectively insulate the surrounding chamber from the heat which is transmitted to the chimney, particularly in its lower portion, by the heated vapors rising therein, and thus improve the extent of vapor condensation in the chamber.

Although the vapor condensation and return system of the pump construction so far described is highly efficient, there is a tendency for a small quantity of vapors to escape into the system being evacuated or to the backing pump. To prevent such loss of vapors, the invention provides novel water-cooled baffle units between the low pressure end of the pump and the system being evacuated and between the high pressure end of the pump and the backing pump, as will now be described.

Referring to Fig. 1, there is attached to the flange 12 of cylinder 10 a hollow, vertically disposed cylinder 90 of like diameter to the cylinder 10 and forming a continuation thereof. Cylinder 90 is provided at its lower end with an annular projecting flange 92 by which it is attached to flange 12 and at its upper end with a like flange 94 by which it may be connected into the system being evacuated (not shown). The cylinder is surrounded by a jacket 96 seated at its opposite ends against the flanges 92 and 94 and providing a space therebetween and the cylinder 90 for cool water which is supplied through a pipe 98 opening at opposite ends through the jacket 96 and the jacket 16 of cylinder 10.

Near the base of cylinder 90, a pipe 100 projects inwardly approximately to the axis of the cylinder, thence upwardly along the cylinder axis to near the upper end of the cylinder, thence outwardly through the cylinder wall and its jacket. On the vertical portion of this pipe are fixed a number of baffle plates 102, two such plates of circular shape being shown in the drawings. To the inner surface of the cylinder are fixed a like number of baffle rings 104, alternating with the plates 102 and having central apertures 105 surrounding the pipe 100 of a shape and size corresponding to the shape and size of the plates 102.

The upper end of the conduit 30 is similarly equipped with a jacket 110 providing a water channel therebetween and the outer surface of the conduit 30 which is sealed at opposite ends and supplied with water through a pipe 112 extending into the conduit 30 through the curved lower part thereof and thence upwardly along the axis of the conduit to near its upper end, where a lateral extension thereof opens through the wall of the conduit 30 into the water channel. The pipe 112 is provided with a number of baffle plates 114 like the baffle plates 102 and the inner surface of the conduit 30 is provided with a number of baffle rings 116 like the baffle rings 104 and similarly alternating with the baffle plates.

In use, the lower end of pipe 112 is connected to a source of cool water (not shown) which flows upwardly in pipe 112 into the passage between the jacket 110 and conduit 30, thence through connecting pipes 118 and pipe 82 into the space between cylinder 10 and its jacket 16, thence through pipe 98 into the passage between cylinder 90 and its jacket and thence through pipe 100 out of the apparatus where it may be returned for recirculation.

The baffle plates 102 and 114 are constantly cooled by the water flowing through the pipes 100 and 112 and the baffle rings 104 and 116 are similarly cooled by the water flowing over the surface of cylinder 90 and conduit 30, respectively. These baffle plates are so arranged as to intercept any vapors escaping from the main pumping cylinder and condense them. Condensed vapors on the baffles and walls of cylinder 90 flow down into cylinder 10 and thence downwardly into pipe 74 and thence back to the boiler. Condensed vapors on the baffles and walls of conduit 30 flow downwardly along the conduit walls to the pipe 74. A narrow baffle ring 120 in conduit 30 just beyond the pipe 74 has an opening 122 therethrough at the bottom of the conduit to permit the pumping liquid flowing downwardly along the conduit to pass therethrough to pipe 74.

In the modified pump construction partially shown in Figs. 3 to 5 there is provided a vertically disposed cylinder 200 having a jacket 201, like the cylinder 10 and jacket 16 of Fig. 1, the cylinder connected, at its upper end (by means not shown), to a system to be evacuated and, at its lower end, to a conduit 202 communicating with a backing pump. A vapor chimney 204 rises into the interior of the cylinder and is provided at its upper end with an umbrella jet formed by ports 206 in the chimney and an inverted conical shield 208, these parts being also like those shown in Fig. 1.

To the inner wall of the cylinder 200, below the upper end of the chimney, there is fastened a ring 210, and a second ring 212 is mounted upon, and surrounds the chimney opposite the ring 210. These rings 210 and 212 are thicker in the middle than at their upper and lower ends and form therebetween a restricted passage 214 in the pumping chamber having a cross-sectional shape similar to that of a passage 60 of Fig. 1. In this case, however, as shown in Fig. 5, the single passage 214 is continuous about the chimney. In the chimney 204, above the passage 214 and below the apertures 206, is provided another ring of ports 216. Fastened to the chimney above the ports 216 is an inverted, cup-shaped deflector 218 which projects laterally from the chimney, then downwardly and outwardly to adjacent the upper end of ring 210. Also fastened to the chimney, below ports 216 is a second deflector 220 projecting laterally from the chimney toward deflector 218 thence downwardly and inwardly to adjacent the upper end of ring 212. The vertically extending portions of deflectors 218, 220 form therebetween a vapor duct 222 which is continuous about the chimney, this duct being similar in cross-section to a nozzle 68 of Fig. 1 and having its lower end similarly disposed with relation to the passage 214.

The space between the laterally extending portions of deflectors 218, 220 is subdivided into a number of smaller, subpassages between the chimney and duct 222 by means of vertically arranged flues 224 extending through these portions of the deflectors (Figs. 3 and 4) and forming pas-

sages for the flow of vapors and gases downwardly between the deflectors 220 and the chimney.

The operation of the jet unit formed by ports 216, deflectors 218, 220 and flues 224, in relation to passage 214, is substantially like the operation of the jet comprising ejectors 62 of Fig. 1 in relation to passages 60. The vapors flowing from ports 216 are subdivided by the sides of flues 224 into separate streams which re-unite as they pass the flues and flow in a single expanding stream from the duct 222, the stream contracting, then expanding as it flows downwardly between the rings 210, 212. Vapors and gases in the chamber above the deflector 218 flow downwardly between said deflector and the inner wall of cylinder 200 and also, by means of the flues 224, downwardly into the space between the inner deflector 220 and chimney 204. Thus both sides of the expanding vapor stream are exposed to the vapors and gases in the pumping chamber and an efficient pumping action thereof is obtained.

The vapors condensing in the cylinder 200 and duct 202 are returned to the boiler 226 through a pipe 228 and T connection 230.

With apparatus as shown in Fig. 1, there is sometimes encountered a tendency of vapors supplied to the top jet to condense before reaching the passages 60 to a greater extent than is desirable. To remedy this condition, the invention provides a novel boiler construction, of which a form is shown in Fig. 3, which enables heating of the vapors rising from the liquid in the boiler so that they reach the upper jet in a somewhat less readily condensable condition.

Referring to Fig. 3, the boiler 226 is shown as provided with bottom plate 232 having a central opening 234 capped by an inverted tube 236 which rises into the lower part of the chimney 204 and is closed at its upper end. Within this tube 236 there is contained an electric heating element 238. Similar elements 240 are disposed immediately below the plate 232.

In operation, the pumping liquid in the boiler is vaporized by the heat from elements 240 and the vapors, as they rise in the chimney, are heated by heat from element 238 radiating from tube 236. A jacket 242 enclosing an evacuated space 244 about the chimney, similar to the jacket 84 of Fig. 1, prevents any substantial heating of the pumping chamber by the element 238.

An additional heating element may, if desired, be provided about the lower part of the chimney between the base of the cylinder and the top of the boiler, or may be used in place of the interior heating element 238 and tube 236 shown. However, we have found that the arrangement shown is generally sufficient of itself and is superior to an exterior heating of the base of the vapor chimney both because the latter arrangement has a greater tendency to heat the pumping chamber and because, with the arrangement shown, the vapors receiving the most heat are at the center of the chimney and have a tendency to rise past the ports 216, which receive the less heated vapors nearer the walls of the chimney, as is desirable.

It will be understood that we have illustrated and described herein preferred embodiments only of apparatus of the invention and that the invention is to be considered as limited thereto only in so far as may be required by the appended claims.

We claim:

1. A diffusion pump having, in combination, conduit means forming a pumping chamber having a first end portion adapted for connection to

a system to be evacuated and a second end portion adapted for connection to a pressure reducing means, said chamber comprising at least one passage for the flow of vapors from said first end portion to said second end portion of the chamber of restricted cross-section relative to said first end portion of the chamber, a first jet for discharging pumping vapors into said first end of the chamber, a second jet for discharging pumping vapors into said chamber comprising a plurality of vapor ducts within said first end portion of the chamber arranged in laterally spaced relation about the axis of the chamber and providing openings therebetween through said jet, each said duct provided with a nozzle for directing vapors therefrom into the mouth of a said passage, and means for supplying pumping vapors to both of said jets.

2. A diffusion pump having, in combination, conduit means forming a pumping chamber having a first end portion adapted for connection to a system to be evacuated and a second end portion adapted for connection to a pressure reducing means, said chamber comprising a plurality of sub-passages for the flow of vapors and gases from said first end portion to said second end portion of the chamber, said sub-passages being of smaller cross-section than said first end portion of the chamber and being arranged in laterally spaced relation about the axis of the chamber, a first jet for discharging pumping vapors into said first end of the chamber, a second jet comprising a plurality of vapor ducts arranged in said chamber for discharging individual streams of pumping vapors into the mouths of said sub-passages, and means for supplying pumping vapors to both of said jets.

3. In a diffusion pump, the combination, with means forming a pumping chamber adapted for connection at one end to a system to be evacuated and at the other end to a pressure reducing means, of a jet for discharging pumping vapors into said chamber between the ends thereof, said jet comprising a pair of deflectors projecting from a wall of said chamber therein and spaced longitudinally of said wall, said deflectors having their inner ends spaced between the walls of said chamber, a plurality of flues extending through and between said deflectors, said flues having their sides closed to the space between said deflectors and their opposite ends open to the chamber, and means for supplying pumping vapors to the space between said deflectors.

4. A diffusion pump having, in combination, conduit means forming the outer wall of a pumping passage, tubular means in said conduit means having opposite walls inwardly sloped from each end to form a portion of said passage of diminishing cross-section between its ends, jet means including a nozzle for directing a stream of pumping vapor into the inlet end of said passage portion formed by said tubular means, said nozzle providing a vapor outlet passage of increasing cross-section toward its outer end and having its outlet end directed axially of the pumping passage portion formed by said tubular means and of substantially smaller cross-section than the inlet end of said passage portion, jet means for diffusing pumping vapor into said pumping passage between said first named jet means and the inlet end of said conduit means, and means for simultaneously supplying pumping vapor to each of said jet means.

5. A diffusion pump having, in combination,

a casing forming the exterior wall of a pumping chamber adapted for connection at one end to a system to be exhausted and at the other end to a pressure reducing means, a vapor chimney extending into said chamber, jet means for discharging heated pumping vapors from said chimney into said passage, a boiler outside of said chamber for supplying heated vapors to said chimney, a jacket surrounding at least a part of the chimney within the chamber, said jacket providing therebetween and said chimney a substantially coextensive and evacuated sealed space insulating the chimney against transmission of heat to said chamber.

6. In combination with a diffusion pump having a pumping chamber for connection between a system to be evacuated and a low pressure producing system and means for diffusing condensable pump operating vapors into said chamber, means for conducting gases between said chamber and one of said systems and for preventing escape of uncondensed vapors from said chamber

therethrough comprising a conduit connected at one end into said chamber and adapted for connection at the opposite end into one of said systems, a fluid conductive pipe extending longitudinally of the interior of said conduit, a first set of baffles mounted in longitudinally spaced relation in said pipe and projecting laterally therefrom toward the inner walls of said conduit, a second set of baffles secured to the inner wall of said conduit in alternate relation with the baffles of said first set, the baffles of said second set each projecting laterally toward said pipe and substantially surrounding the pipe with their inner edges spaced from said pipe, means for circulating cooling fluid through said pipe, means for circulating cooling fluid over the outer surface of said conduit, and means for collecting the liquid of condensed pumping vapors condensing in said conduit.
